SIPHON FOR FILLING MILK CANS

William J. Tamminga, Goshen, N. Y., assignor to
Wiz-Products, Inc., Goshen, N. Y., a corpora-
tion of New York

Application May 3, 1949, Serial No. 91,041

5 Claims. (Cl. 251—115)

1

This invention is a siphon, through the use of which, conventional twenty or forty quart milk delivery cans may be filled at a creamery or other milk depot from a bulk supply of milk.

The siphons heretofore employed for this purpose have been provided at the lower ends of their shorter and longer legs with valves adapted to be opened by contact with the bottom of the can and with the bottom of a tank containing the bulk supply of milk, to permit milk to flow from the tank into the can. These valves are so constructed that, when the siphon is lifted out of the can, the valves automatically close to keep the siphon charged for the filling of the next can. However, the valves of all such prior siphons have uniformly embodied a number of metal parts threaded together. These constructions have not proven satisfactory for many reasons. For example, the metal valves, which require contact with the can and tank, dent or deform the cans, are difficult to maintain tight sealing and the screw threaded connections are unsanitary and form a harbor for germs, bacteria and other foreign matter.

The primary purpose of the present invention is to provide an improved valve arrangement for siphons of the character described. My valve arrangement is absolutely sanitary and that portion of the valve which contacts with the can and tank bottom is of rubber so that it cannot dent or otherwise harm these parts. The structure is also readily demountable and may be maintained clean and sterile at all times.

Features of the invention, other than those adverted to, will be apparent from the herein-after detailed description and appended claims, when read in conjunction with the accompanying drawing.

The accompanying drawing illustrates one practical embodiment of the invention, but the construction therein shown is to be understood as illustrative, only, and not as defining the limits of the invention.

Figure 1 shows a can filling siphon embodying the present invention and the manner of its use, the can and tank being illustrated in section.

Figure 2 is a section on the line 2—2 of Figure 1.

Figure 3 is an underneath plan view of the valve supporting plate shown in section in Figure 2.

In the accompanying drawing, 1 indicates a table to support a tank 2 containing a pool 3 of milk, adapted to be transferred in desirable quantities into a conventional milk delivery can.

5 adapted to be thereby filled. The siphon is provided with a short leg 6 and a long leg 7 connected near their tops by a cross tube 8. The upper end of the leg 7 has a screw cap 9 threaded thereto with an appropriate interposed gasket to normally hermetically seal the leg 7 at this point and a similar removable seal 9a is associated with one end of the cross tube 8. The purpose of these removable seals 9 and 9a is to permit 10 thorough cleaning of the tubes, by the passage of a brush therethrough, when the seals are removed.

Upon the lower end of each of the legs 6 and 15 7 is mounted a globular metallic valve chamber 10. This valve chamber 10 is securely welded in place with appropriate fillets to eliminate sharp corners or crevices in which foreign matter might lodge.

Positioned within the lower end of each leg is 20 a cylindrical guide, preferably in the form of a sleeve 11, having a nice sliding fit within the leg and provided at its lower end with an external flange or enlarged head 12 which forms a limiting stop against upward movement of the guide 25 beyond the position shown in full lines in Figure 2.

Beneath the lower end of the sleeve 11 is a 30 valve supporting plate 13. This plate is spaced from the lower end of the sleeve 11 by a plurality of wire spacers 14, shown three in number, although any number of spacers may be used. In any event, these spacers are preferably welded to both the sleeve 11 and plate 12, so as to form 35 a unit therewith and they serve to maintain the sleeve and plate in axial alignment. The outer diameter of the flange 12 and the plate 13 are preferably very slightly smaller than the circular coaxial mouth 15 at the lower end of the valve chamber, so that the sleeve and plate may be 40 moved into and out of the position shown in Fig. 2 by passing them collectively through the mouth 15 of the valve chamber.

The under side of the plate 13 is provided with 45 two or more cylindrical lugs 16 perforated at 17 near their lower ends. These lugs permit the mounting of a valve 18 on said plate. The valve 18 comprises a circular disk of rubber or some other suitable elastic material. It is fairly thick and rugged throughout its body but its circumferential margin is radially tapered to a somewhat thinner edge. This edge is thus rendered 50 more readily conformable with the inner surface of the valve chamber immediately above the mouth 15 when the valve disk is lowered into contact therewith. To permit of this, the diameter 55

of the valve disk is greater than the diameter of the mouth 15. The valve disk is provided with a depending coaxial integral stem 19, so that the valve disk and stem, collectively, are of substantially T-shape cross section and circular in plan. The valve disk is provided with holes adapted to be snugly passed over the lugs 16 and the valve secured in place upon the plate by one or more locking wires 20, passed through holes 17 or by cotter pins or in any other suitable manner.

In assembling the parts, the sleeve 11 and plate 13 are first introduced into the casing at the lower end of the siphon leg as a unit. The valve disk is then bent or flexed sufficiently to permit it to be passed through the mouth 15 into the casing 10. The valve is then rotated to bring the holes in the valve into registration with the lugs 16 and the lugs are passed through the holes, after which the locking wires 20 are applied to lock the valve to the guide.

The valve stem 19 has a length approximately equal to the internal diameter of the valve chamber 10. Thus, when a siphon equipped with my construction is used as shown in Figure 1, the seating of the valve stems against the bottoms of the can and tank will impose the weight of the siphon upon these valve stems and raise the valves until the flanges 12 engage with the lower ends of the legs 6 and 7. This will position the valve disks about midway of the height of their valve casings, so that milk may flow through the mouths 15 and about the peripheries of the valve disks. At the same time the mouths of both valve casings will be supported in spaced relation above the bottom of the can and tank, as clearly shown in Figure 2. When thus positioned, both legs of the siphon will be unsealed and milk will flow from the tank 2 through the siphon into the can until the can is filled to the desired level, which will be determined by the operator. When this level has been reached, the siphon is lifted and immediately the weight of the valves, sleeves 11, and plates 13 will cause the valves to descend so that the periphery of each valve disk will seat against the inner surface of the corresponding valve casing above the mouth 15 thereof before the legs of the siphon leave the bodies of milk in the can and tank and thus the siphon will remain charged for immediate use for the filling of the next can. It will thus be manifest that no metal part of the structure need ever touch the can. The only contact with the can or tank is made by the lower ends of the rubber valve stems 19 which can do no damage.

Apparatus of the character described requires frequent cleaning in the interest of sanitation. To allow of this, the locking wires may be readily removed to disconnect the valve from the plates 13 and these valves and the guides and plates may then be readily removed. If the seals 9 and 9a are then removed, a brush may be passed through the tubes of the siphon to thoroughly clean the same.

The structure which I have described is economical to manufacture, thoroughly efficient in its operation and absolutely sanitary in use. Since the valve casing is substantially globular, the inner surface of the same about the mouth thereof constitutes a valve seat of considerable breadth, so that the external diameter of the valve disk is not critical and will not interfere with proper seating of the valve. Furthermore, since the valve is of rubber, careful machining of this seat is not necessary.

Siphons of this character are commonly operated by hand, although, if desired, any suitable mechanical, electrical or pneumatic means for raising and lowering the siphons may be utilized without departing from this invention.

The foregoing detailed description sets forth the invention in its preferred practical form, but the invention is to be understood as fully commensurate with the appended claims.

Having thus fully described the invention, what I claim as new and desire to secure by Letters Patent is:

1. A flow controlling device for a siphon tube comprising: a valve casing having a circular bottom opening forming a mouth for the passage of liquid and surrounded by an internal valve seat, a rubber valve disk positioned within the valve casing and of greater diameter than the mouth thereof to normally engage with said seat, said rubber valve disk having a depending valve stem projecting at all times through said mouth and having a relatively soft resilient lower end, a guide secured to said valve disk and guided for sliding movement, and a stop for limiting the upward movement of the valve.

2. A flow controlling device for a siphon tube comprising: a valve casing having a circular bottom opening forming a mouth for the passage of liquid and surrounded by an internal valve seat, a soft rubber valve disk positioned within the valve casing and of greater diameter than the mouth thereof to normally engage with said seat, said soft rubber valve disk having an integral coaxial depending soft rubber valve stem projecting at all times through said mouth, a guide secured to said valve disk and guided for vertical movement, and a stop for limiting upward movement of the valve.

3. A flow controlling device for a siphon tube comprising: a valve casing having a circular bottom opening forming a mouth for the passage of liquid and surrounded by an internal valve seat, a soft rubber valve disk positioned within the valve casing and of greater diameter than the mouth thereof to normally engage with said seat, said rubber valve disk having an integral coaxial depending soft rubber valve stem projecting at all times through said mouth, a guide adapted for vertical sliding movement coaxially of the valve and carrying a valve supporting plate, means for detachably securing the valve to said plate, and a stop on said guide for limiting the upward movement of the valve.

4. A flow controlling device for a siphon tube comprising: a substantially globular valve casing provided at its bottom with a circular opening forming a mouth surrounded by an internal valve seat, a guide adapted for sliding movement coaxially of the valve and carrying a valve supporting plate, a stop for limiting the upward movement of said plate, said guide and plate being of overall diameter to be passed into and out of the casing through the mouth thereof, the rubber valve disk of greater diameter than the diameter of said mouth and of less diameter than the greatest internal diameter of the casing, and means for detachably securing said valve disk to said plate within the casing, said valve disk having a depending integral rubber valve stem projecting at all times through the mouth of the casing.

5. A flow controlling device for a siphon tube comprising: a substantially globular valve casing provided at its bottom with a circular opening forming a mouth surrounded by an internal

valve seat, a guide adapted for sliding movement and carrying a valve supporting plate coaxial with the valve, and a stop for limiting the upward movement of said plate, said guide and plate being of overall diameter to be passed into and out of the casing through the mouth thereof, and said plate being provided on its under side with downwardly projecting valve attaching lugs, a rubber valve disk of greater diameter than the diameter of said mouth and of less diameter than the greatest internal diameter of the casing, said valve disk having therein attachment openings for detachable engagement with the lugs of said plate, said valve disk also being provided with a depending integral rubber valve stem of sufficient length 15

to extend at all times through and below the mouth of the casing.
